Primary Examiner — Ian Simmons*Assistant Examiner* — Shannon Morgan*(74) Attorney, Agent, or Firm* — Michael J. Striker**CLAIM**

The ornamental design for a bowl, as shown and described.

DESCRIPTION

FIG. 1 is an exploded perspective view of a bowl shown in an open position showing my new design;

FIG. 2 is an exploded front elevation view thereof;

FIG. 3 is an exploded rear elevation view thereof;

FIG. 4 is a left side exploded view thereof;

FIG. 5 is a right side exploded view thereof;

FIG. 6 is an exploded top plan view thereof; and

FIG. 7 is an exploded bottom plan view thereof;

FIG. 8 is a perspective view of the bowl shown in FIG. 1 shown in a closed position showing my new design;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The broken lines shown in FIGS. 4, 7, and 14 represent portions of the bowl that form no part of the claimed design.

1 Claim, 14 Drawing Sheets(56)
